Primary Examiner — T. Chase Nelson*Assistant Examiner* — Jonathan J. Han(74) *Attorney, Agent, or Firm* — Neugeboren O'Dowd PC(57) **CLAIM**

The ornamental design for a magazine, as shown and described.

DESCRIPTION

FIG. 1 is a front, right, bottom perspective view of a magazine showing my new design;

FIG. 2 is a right side elevation view of the magazine of FIG. 1;

FIG. 3 is a left side elevation view of the magazine of FIG. 1;

FIG. 4 is a rear elevation view of the magazine of FIG. 1; FIG. 5 is a front elevation view of the magazine of FIG. 1; FIG. 6 is a top view of the magazine of FIG. 1; and, FIG. 7 is a bottom view of the magazine of FIG. 1.

The shade lines in the Figures show contour and not surface ornamentation.

The broken lines in the Figures show portions of the magazine and environment that form no part of the claimed design.

1 Claim, 6 Drawing Sheets(56)
